UNITED STATES PATENT OFFICE

121,623

DESIGN FOR A PROPELLER SHAFT STRUT OR THE LIKE

Jack Casey, Grove, Okla.

Application April 17, 1940, Serial No. 91,732

Term of patent 14 years

To all whom it may concern:

Be it known that I, Jack Casey, a citizen of the United States, residing at Grove, in the county of Delaware and State of Oklahoma, have invented a new, original, and ornamental Design for a Propeller Shaft Strut or the like, of which the following is a specification, reference being had to the accompanying drawing, forming part thereof.

Figure 1 is a bottom perspective view of a propeller shaft strut or the like showing my new design.

Figure 2 is a side elevational view thereof.

Figure 3 is an end elevational view looking from right to left in Figure 2.

Figure 4 is a transverse vertical sectional view taken through Figure 3 approximately on the line 4-4 and looking upwardly in the direction of the arrow.

I claim:

The ornamental design for a propeller shaft strut or the like, as shown.

JACK CASEY.
